UNITED STATES PATENT OFFICE.

ALBERT OWEN HOLTOM AND JAMES B. CROCKETT, OF NEW YORK, N. Y.

DESIGN FOR A RADIATOR FOR AN AUTOMOBILE.

58,907.

Specification for Design.

Patented Sept. 6, 1921.

Application filed February 17, 1920. Serial No. 359,351. Term of patent 7 years.

To all whom it may concern:

Be it known that we, ALBERT O. HOLTOM and JAMES B. CROCKETT, subjects of the King of England, and citizens of the United States, residing at New York, in the county of New York and State of New York, have invented a new, original, and ornamental Design for Radiators for Automobiles, as shown in the accompanying drawing and described in the following specification.

Figure 1 is a front elevation, and Fig. 2 is a bottom plan view of a radiator for automobiles showing our new design.

We claim:

The ornamental design for a radiator for an automobile as shown and described.

ALBERT OWEN HOLTOM.
JAMES B. CROCKETT.
